UNITED STATES PATENT OFFICE.

HAROLD L. BLOOD, OF NORTH PLAINFIELD, NEW JERSEY, ASSIGNOR TO NILES-BE-MENT-POND COMPANY, OF NEW YORK, N. Y., A CORPORATION OF NEW JERSEY.

CONTROL SYSTEM.

Application filed August 4, 1923. Serial No. 655,739.

My invention relates to control systems for operating machine tools and particularly to control systems for operating planers.

One object of my invention is to provide a control system that shall operate a reciprocating member and effect a feeding movement of a cutting tool at each end of the stroke of the reciprocating member and that shall insure a delay in the feeding movement at one end of the stroke of the reciprocating member.

Another object of my invention is to provide a control system of the above indicated character that shall automatically reverse the direction of rotation of a main motor at each end of the stroke of the reciprocating member and operate a feed motor to effect a feeding movement and that shall insure a prompt feeding movement at one end of the stroke and a delayed feeding movement at the opposite end of the stroke.

A further object of my invention is to provide a control system of the above indicated character that shall be provided with two main switches for operating a main motor in a forward and in a reverse direction and two feed switches for operating the feed motor in a forward and in a reverse direction and that shall so interlock the switches as to effect simultaneous operation of one main and one feed switch at one end of the stroke of the reciprocating member and consecutive operation of one main switch and one feed switch at the opposite end of the stroke of the reciprocating member.

In operating many machine tools having a reciprocating member and particularly in operating a planer, it is very often desirable to effect a feeding movement by the cutting tool at each end of the stroke of the reciprocating table. When operating a planer to effect a feeding movement at each end of the stroke of the table, it is desirable to effect operation of the feed motor simultaneously with the operation of the main motor at the end of a return stroke. The prompt operation of the feed motor at the end of the return stroke to effect a feeding movement of the tool can in no way spoil the work which is being operated on. However, at the end of the cutting stroke, trouble is liable to be experienced if the feed motor is operated simultaneously with the main motor without allowance for somewhat of over-travel by the cutting tool. By reason

of the inertia of the moving parts, somewhat of drift of the table is effected after the pilot switch is operated to reverse the direction of rotation of the main motor. Account is sometimes taken of such drift of the table by effecting a cutting operation by the cutting tool during such drift. If the feed motor were operated before the cutting tool reaches the end of the work, the tool would be moved transversely while effecting a feeding cut. The moving of the cutting tool across the work while effecting a cut is liable to spoil the work being operated on.

In a control system constructed in accordance with my invention, the feeding operation is effected promptly at the end of the return stroke of the table and is delayed at the end of the cutting stroke. The system is provided with two main switches, two feed switches, and the usual accelerating switches. One of the feed switches is interlocked with one of the main switches in order to prevent the operation of such feed switch at the end of the cutting stroke of the planer table until after the operation of the main switch. By such means, a delayed operation of the feeding movement is effected at the end of the cutting stroke.

In the accompanying drawing:

Figure 1 is a front elevational view of a planer adapted to be operated in accordance with my invention.

Fig. 2 is a diagrammatic view of a control system constructed in accordance with my invention.

Referring to Fig. 1 of the drawing, a planer is illustrated having a bed 1, a table 2 and uprights 3 for supporting a cross rail 4. The table 2 is reciprocated by a main motor 5 which is connected to the table by suitable gearing 6. The cross rail 4, which is mounted on the uprights 3, carries a tool head 7 which in turn carries a cutting tool 8. A feed motor 9 is operated on the arch (not shown) of the planer. The feed motor 9 is connected to a shaft 10 for effecting feeding and traversing operations of the cutting tool in a well known manner. For a more complete description of the mechanical construction of the planer, reference may be had to the patent to Greenleaf and Keefer, No. 1,299,192, dated April 1, 1919.

Upon the bed 1 of the planer is mounted a pilot switch 11 which controls the operation not only of the main motor 5 but also of

the feed motor 9. The pilot switch 11 is operated by two movable dogs 12 and 13 which are mounted on the table 2. At the end of the cutting stroke of the table, the 5 dog 12 engages a lever 14 for operating the pilot switch 11 in one direction. At the end of the return stroke, the dog 13 engages a lever 15 for operating the pilot switch in an opposite direction. The levers 14 and 15 10 are connected to the pilot switch 11 by links 16.

Referring to Fig. 2 of the drawing, the main motor 5 is shown comprising a shunt field-magnet winding 17, a series field-magnet winding 18, an emergency winding 19 similar in every way to the emergency winding shown and described in the patent to Foster 1,252,897 granted January 8, 1918, a commutator winding 20, and an armature 21. 20 The feed motor 9 comprises an armature 22, a series field-magnet winding 23, and a shunt field-magnet winding 24. The main motor 5 is controlled by two main magnets 25 and 26 and two accelerating magnets 27 and 28. 25 The feed motor 9 is controlled by two feed magnets 29 and 30 and one accelerating magnet 31. A suitable circuit breaker 32 is provided for preventing operating of the system under over-load and low voltage circuit 30 conditions.

A pendent switch 33 is provided for operating the main and the feed motors at will and for insuring against any automatic operation of such motors, during the manual 35 operation. A limit switch 34 is provided for limiting the feeding movements of the motor 9. An accelerating resistor 35, which is controlled by the accelerating switches 27 and 28, is provided in the circuit of the main 40 motor 5. An accelerating resistor 36, which is controlled by the accelerating switch 31, is provided in the circuit of the feed motor 9. A discharge resistor 37 is provided across the 45 shunt field-magnet winding 17 to cushion the effect of breaking of this shunt field magnet winding and a dynamic-braking resistor 38 is provided in the circuit of the feed motor 9.

The main switch 26 comprises a pivotally 50 mounted switch arm 39 having two contact members 40 and 41 mounted thereon. In the released position of the switch arm 39, the contact member 41 engages a stationary contact member 42 and in the operative position 55 of the switch arm, the contact member 40 engages a stationary contact member 43. The switch arm 39 carries another contact member 44 which is adapted to engage a stationary contact member 45 when the switch arm 60 is in an operative position. The engagement 65 between the contact members 44 and 45 serves to complete a circuit for effecting operation of the accelerating switches 27 and 28. A main magnet 46 is provided for operating the switch arm and a holding magnet 47 is

provided for preventing operation of the switch arm when the main switch 25 is operated and when a dynamic-braking current is flowing through the main motor 5. The main switch 26 serves to operate the main 70 motor 5 for effecting a cutting stroke by the planer.

The main switch 25 comprises a pivotally mounted switch arm 48 having three contact members 49, 50 and 51 mounted thereon. In the released position of the switch arm, the contact member 49 engages a stationary contact member 51. In the operative position of the switch arm, the contact member 50 engages stationary contact member 52, and the contact member 51 closes a switch 53 for effecting operation of the accelerating switches 27 and 28. A main magnet 54 is provided for effecting operation of the switch arm 48 and a holding coil 55 is provided for preventing operation of the switch arm when the main switch 26 is operated and when a dynamic-braking current is flowing through the main motor. A pin 56, which projects from the side of the switch arm 48, is adapted to open a switch 57 when the switch 25 is operated. The switch 57 serves normally to short circuit a resistor 58. However, upon operation of the switch arm 48 to open the switch 57, the resistor 58 is connected with a resistor 59 in circuit with the shunt field-magnet winding 17. The resistors 58 and 59, which are thus included in circuit with the shunt field-magnet winding 17, serve to effect a relatively rapid return stroke by the planer table.

The accelerating switch 27 comprises a pivotally mounted switch arm 60 having a contact member 61 and an insulated contact member 62 mounted thereon. In the released position of the switch arm, the contact member 62 bridges two stationary contact members 63 and in the operative position of the switch arm, the contact member 61 engages a stationary contact member 64. 105 A magnet 65 is provided for effecting operation of the switch arm 60.

The accelerating switch 28 comprises a pivotally mounted switch arm 66 having a contact member 67 and an insulated contact member 68 mounted thereon. The insulated contact member 68 is adapted to bridge stationary contact members 69 in the released position of the switch arm. The contact member 67 is adapted to engage a stationary contact member 70 in the operative position of the switch arm. A magnet 71 is provided for operating the switch arm 66.

The feed switch 29 comprises two pivotally mounted switch arms 72 and 73, which are connected together by means of a link 74. The switch arm 73 carries a contact member 75 and the switch arm 72 carries two contact members 76 and 77. In the re-

leased position of the switch arms, the contact member 77 engages a stationary contact member 78. In the operative position of the switch arms, the contact members 75 and 76 are adapted, respectively, to engage stationary contact members 79 and 80. A magnet 81 is provided for effecting operation of the switch arms and a holding coil 82 is provided for preventing operation of the switch arms when a dynamic-braking current is flowing through the feed motor 9.

The feed switch 30 comprises two pivotally mounted switch arms 83 and 84 which are connected together by a link 85. The switch arm 84 carries a contact member 86 and the switch arm 83 carries two contact members 87 and 88. The contact member 88 is adapted to engage a stationary contact member 89 in the released position of the switch arms and the contact members 86 and 87 are respectively adapted to engage stationary contact members 90 and 91 in the operative position of the switch arms. A magnet 92 is provided for effecting operation of the switch arm 83 and a holding coil 94 is provided for preventing operation of the switch arms when a dynamic-braking current is flowing through the feed motor 9.

The accelerating switch 31 comprises a switch arm 95, having a contact member 96 mounted thereon. The contact member 96 engages a stationary contact member 97 in the operative position of the switch arm. A magnet 98 is provided for effecting operation of the switch arm 95.

The pilot switch 11 comprises three contact segments 100, 101 and 102. The contact segment 100 is adapted to engage contact fingers 103 to 106, inclusive, for controlling the operation of the feed switches 29 and 30. The contact segment 101 is adapted to engage stationary contact fingers 107 to 110, inclusive, for controlling the operation of the accelerating switches 27 and 28. The contact segment 102 is adapted to engage the stationary contact fingers 111 to 114, inclusive, for controlling the operation of the main switches 25 and 26. The limit switch 34, which is operated by the shaft 10, comprises contact segments 115 to 118, inclusive. The contact segments which are mounted on a suitable drum are, respectively, adapted to engage stationary contact fingers 119 to 122, inclusive.

The pendent switch 33 comprises two switch rods 123 and 124 which, respectively, control the operation of the main motor 5 and the feed motor 9 under certain conditions. The rod 123 carries two contact segments 125 and 126. In the position shown in the drawing, the contact segment 125 bridges the contact members 127 and 128 to complete a circuit for operating the accelerating switches 27 and 28. The contact seg-

ment 126 bridges the contact members 129 and 130 for permitting operation of the main switches 25 and 26, by means of the pilot switch 11. Upon moving the rod 123 upward, the contact segments 125 and 126 disengage the contact members to prevent any automatic operation of the main switches 25 and 26 or the accelerating switches 27 and 28 by the pilot switch 11. In the upper position of the rod 123, the contact segment 126 may be turned in one direction for bridging contact members 131 and 132 to effect operation of the main switch 26 or may be moved in an opposite direction for bridging contact members 133 and 134 to effect operation of the main switch 25.

The rod 124 carries two contact segments 135 and 136. In the lower position of the rod 124, the contact segment 135 bridges contact members 137 and 138 to complete a circuit for effecting operation of the accelerating switches 27 and 28 by means of the pilot switch 11. The contact segment 136, in the lower position of the rod 124, bridges contact members 139 and 140 for permitting operation of the main switches 25 and 26 by means of the pilot switch. A third contact segment 141 is provided on the rod 124 for bridging contact fingers 142 and 143 in the lower position of the rod 124. The contact segment 141 completes a portion of a circuit for effecting operation of the feed switch 30 by means of the pilot switch 11. In the raised position of the rod 124, the contact segments 135, 136 and 141 disengage the contact members to prevent operation of the main switches, the accelerating switches, and the feed switches by the pilot switch 11. When the rod 124 is in the raised position, the contact segment 136 may be turned in one direction for bridging contact fingers 145 and 146 to effect operation of the feed switch 30. The contact segment 136 may be moved in an opposite direction for bridging contact members 147 and 148 to effect operation of the feed switch 29.

The circuit breaker 32 comprises two switch arms 150 and 151 which are adapted to be connected to the supply conductors 152 and 153. An over-load coil 154 and a low voltage coil 155 are provided for opening the circuit breaker to protect the system. An arm 156 is provided for engaging contact members 157 and 160, inclusive, to complete an emergency braking circuit upon release of the circuit breaker.

At the end of the return stroke of the planer table 2, the dog 13 engages the lever 15 for operating the pilot switch 11 to move the contact segments 102, 101 and 100 in a clockwise direction, as shown in Fig. 2 of the drawing. The contact segment 102 bridges the contact fingers 111 and 112 for completing a circuit to operate the main

switch 26. The circuit completed by the contact segment 102 extends from the supply conductor 153 through switch arm 151, series winding 18, holding coil 55, contact members 51 and 49, switch arm 48, magnet 46, contact fingers 111 and 112, which are bridged by the contact segment 102, contact fingers 139 and 140, which are bridged by the contact segment 136, contact fingers 129 and 130, which are bridged by the contact segment 126, over-load coil 154, and the switch arm 150 to the supply conductor 152. The main switch 26 is operated and a circuit is completed through the main motor 5.

The circuit through the main motor 5 extends from the supply conductor 153 through switch arm 151, series field-magnet winding 18, holding coil 55, contact members 51, 49, switch arm 48, accelerating resistor 35, winding 20, armature 21, switch arm 39, contact members 43 and 40, coil 154, and the switch arm 150 to the supply conductor 152. The motor 5 is operated in a direction to effect a cutting stroke by the planer.

The contact segment 101 bridges the contact fingers 109 and 110 for effecting operation of the accelerating switches 27 and 28 by the counter electromotive force developed by the main motor 5. The circuit for operating the accelerating switches extends from one terminal of the armature 21 through the switch arm 39, contact members 44 and 45, magnets 65 and 71 of the accelerating switches in parallel, contact members 127 and 128, which are bridged by the contact segment 125, contact fingers 137 and 138, which are bridged by the contact segment 135, contact fingers 109 and 110, which are bridged by the contact segment 101, and the winding 20 to the other terminal of the armature 21. The accelerating switches 27 and 28 are successively operated to short circuit portions of the accelerating resistor 35 from the circuit of the main motor 5. One of the switches 27 and 28 may be rendered slow acting by lengthening the air gap between the pole and the armature thereof.

Prior to the operation of the accelerating switches 27 and 28, the shunt field-magnet winding 17 is connected across the supply conductors 152 and 153 by a circuit which extends from the supply conductor 153 through switch arm 151, winding 17, contact members 63, which are bridged by the contact segment 62, winding 154, and the switch arm 150 to the supply conductor 152. Upon operation of the accelerating switch 27 the circuit of the shunt field-magnet winding 17 extends through the resistor 59, switch 57, coil 154, and the switch arm 150 to the supply conductor 152.

Upon bridging of the contact fingers 105 and 106 by the contact segment 100, a circuit

is completed for operating the feed switch 29. The circuit through the magnet of the feed switch 29 extends from the supply conductor 153 through the switch arm 151, field-magnet winding 23, coil 81, contact fingers 121 and 122, which are bridged by the contact segments 117 and 118, contact fingers 105 and 106, which are bridged by the contact segment 100, contact fingers 140, 139, which are bridged by the contact segment 136, contact fingers 129 and 130, which are bridged by the contact segment 126, winding 154, and the switch arm 150 to the supply conductor 152. The energizing circuit for the magnet of the feed switch 29 is connected directly across the supply conductor 152 and 153 at the end of the return stroke. Accordingly, a prompt feeding operation of the motor 9 is effected. Moreover, it will be noted the feed switch 29 operates simultaneously with the main switch 26.

The circuit completed through the feed motor 9 extends from the supply conductor 153, through the switch arm 151, series field-magnet winding 23, contact members 79 and 75, switch arm 73, armature 22, switch arm 72, contact members 76 and 80, resistor 36, winding 154, and the switch arm 150 to the supply conductor 152. The accelerating switch 31 is operated by the counter electromotive force of the feed motor to short circuit the resistor 36. The feeding movement of the main motor 9 continues until the limit switch 34 is operated for disconnecting the contact segments 117 and 118 from the contact fingers 121 and 122 to open the energizing circuit for the magnet 81.

At the end of the cutting stroke, the dog 12 on the table 2 engages the lever 14 to reverse the position of the pilot switch 11. The contact segments 102, 101 and 100 are given a movement in a counter clockwise direction, as shown in Fig. 2 of the drawing. The contact segment 102 disengages the contact fingers 111 and 112 and bridges the contact fingers 113 and 114. The contact segment 101 disengages the contact fingers 109 and 110 and bridges the contact fingers 107 and 108. The contact segment 100 disengages the contact fingers 105 and 106 and bridges the contact segments 103 and 104. Upon separating the contact segment 102 from the contact fingers 111 and 112, the energizing circuit for the magnet 46 of the main switch 26 is opened to release the switch 26. Thereupon, a dynamic-braking circuit is completed through the main motor 5. The dynamic-braking circuit extends from one terminal of the armature 21 through switch arm 39, contact members 41 and 42, coil 47, coil 55, contact members 49 and 51, switch arm 48, resistor 35, and winding 20 to the other terminal of the armature 21.

The bridging of the contact fingers 113

- and 114 by the contact segment 102 completes a circuit for energizing the magnet 54 of the main switch 25. The circuit for the magnet 54 extends from the supply conductor 153 through the switch arm 151, series field-magnet winding 18, holding coil 47, contact fingers 41 and 42, switch arm 39, magnet 54, contact fingers 113 and 114, which are bridged by the contact segment 102, contact fingers 139 and 140, which are bridged by the contact segment 136, contact fingers 129 and 130, which are bridged by the contact segment 126, winding 154, and switch arm 150 to the supply conductor 152. A circuit is completed through the main motor for operating such motor to effect a return stroke of the planer.

The circuit completed by the switch 25 through the main motor 5 extends from the supply conductor 153 through the switch arm 151, series field-magnet winding 18, holding coil 47, contact fingers 41 and 42, switch arm 39, armature 21, winding 20, resistor 35, switch arm 48, contact members 50 and 52, winding 154 and the switch arm 150 to the supply conductor 152.

The switch arm 48 of the main switch 25 opens the switch 57 to insert the resistor 58 in circuit with the shunt field-magnet winding 17. The inserting of the resistor 58 with the resistor 59 in circuit with the shunt field-magnet winding increases the speed of the return stroke.

The bridging of the contact fingers 107 and 108 by the contact segment 101 completes a circuit through the magnets of the accelerating switches 27 and 28. The circuit through the magnets of the accelerating switches extends from one terminal of the armature 21 through the switch arm 39, switch 53, magnets 65 and 71 in parallel, contact fingers 127 and 128, which are bridged by the contact segment 125, contact fingers 137 and 138, which are bridged by the contact segment 135, contact fingers 109 and 110, which are bridged by the contact segment 101, and the winding 20 to the other terminal of the armature 21. The accelerating switches are operated to short circuit the accelerating resistor 35.

The separating of the contact segments 117 and 118 from the contact fingers 121 and 122 releases the feed switch 29 to complete a dynamic-braking circuit. The dynamic-braking circuit extends from one terminal of the armature 22 through the switch arm 72, contact fingers 77 and 78, resistor 38, contact fingers 88 and 89, and the switch arm 83 to the other terminal of the armature 22. The magnets 82 and 94 are connected across the dynamic-braking circuit to prevent operation of the feed switch 29 or the feed switch 30 until the braking current ceases to flow.

Upon bridging of the contact fingers 103

and 104 by the contact segment 100, a circuit is completed for operating the feed switch 30. The energizing circuit for the feed switch 30 extends from the supply conductor 153 through the switch arm 151, series field-magnet winding 23, magnet 92, contact fingers 119 and 120, which are bridged by the contact segments 115 and 116, contact fingers 103 and 104, which are bridged by the contact segment 100, contact fingers 142 and 143, which are bridged by the contact segment 141, switch arm 48, contact members 50 and 52, winding 154, and switch arm 150 to the supply conductor 152. It will be noted the above circuit for energizing the magnet 92 of the feed switch 30 extends through the main switch 25 and accordingly it is impossible to operate the feed switch 30 to effect a feeding operation at the end of the cutting stroke until after the operation of the main switch 25. Accordingly, it is apparent a delayed feed is effected at the end of the cutting stroke. It will also be noted that such circuit extends through the contact segment 141 of the pendent switch to prevent the closing of the circuit when the rod 124 of the pendent switch is in a raised position.

The circuit completed through the feed motor extends from the supply conductor 153 through the switch arm 151, series field-magnet winding 23, contact members 86 and 90, switch arm 84, armature 22, switch arm 83, contact members 87 and 91, resistor 31, winding 154 and the switch arm 150 to the supply conductor 152.

The above cycle of operations is automatically effected under the control of the pilot switch 11. In case it is desired to operate the main motor 5 at will, the rod 123 of the pendent switch 33 is raised to separate the contact segment 126 from the contact members 129 and 130 and to separate the contact segment 125 from the contact fingers 127 and 128. As heretofore set forth, the separating of the contact segments 125 and 126 from such contact fingers prevents the automatic operation of the main switches 25 and 26, the automatic operation of the feed switches 29 and 30, and the operating of the accelerating switches 27 and 28.

If the rod 123 is raised and the contact segment 126 is turned toward the right, as shown in Fig. 2 of the drawing, to bridge the contact fingers 131 and 132, a circuit is completed for operating the main switch 26. The circuit through the magnet of the main switch 26 extends from the supply conductor 153 through the switch arm 151, series winding 18, holding coil 55, contact members 49 and 51, switch arm 48, magnet 46, contact fingers 131 and 132, which are bridged by the contact segment 126, winding 154 and the switch arm 150 to the supply conductor 152.

The moving of the contact segment 126 towards the left, as shown in Fig. 2 of the drawings, bridges the contact fingers 133 and 134 for operating the main switch 25. The energizing circuit for the main switch 25 extends from the supply conductor 153 through the switch arm 151, series winding 18, holding coil 47, contact fingers 41 and 42, switch arm 39, magnet 54, contact fingers 133 and 134, which are bridged by the contact segment 126, winding 154, and the switch arm 150 to the supply conductor 152.

The rod 124 of the pendent switch, as heretofore set forth, serves to effect operation of the feed motor 9 at will. The moving of the rod 124 upwardly, as shown in Fig. 2 of the drawing, serves to prevent operation of the accelerating switches 27 and 28, to prevent any automatic operation of the main motor 5 and the feed motor 9, and to break the energizing circuit of the feed switch 30 through the main switch 25. Assuming the rod 124 to be in the raised position, a circuit is completed for operating the feed switch 30 when the contact segment 136 is moved towards the right, as shown in Fig. 2 of the drawing. The circuit through the magnet 92 of the feed switch 30 extends from the supply conductor 153 through the switch arm 151, series winding 23, magnet 92, contact fingers 145 and 146, which are bridged by the contact segment 136, winding 154 and the switch arm 150 to the supply conductor 152.

Upon moving the contact segment towards the left, as shown in Fig. 2 of the drawing, the contact fingers 147 and 148 are bridged by the contact segment 136 for completing a circuit to operate the feed switch 29. The circuit through the magnet 81 of the feed switch 29 extends from the supply conductor 153 through the switch arm 151, series winding 23, magnet 81, contact fingers 147 and 148, contact segment 136, winding 154, and the switch arm 150 to the supply conductor 152.

Modifications in the system and in the arrangement and location of parts may be made within the spirit and scope of my invention and such modifications are intended to be covered by the appended claims.

What I claim is:

1. In a control system for a machine tool, the combination with a reciprocating member, a main motor for operating the reciprocating member, and a feed motor for effecting feeding movements of the cutting tool, of means for automatically operating said motors in accordance with the movement of the reciprocating member, and means for varying the time of operating the feed motor with respect to the time of operating the main motor according to the direction of movement of the reciprocating member.

2. In a control system for a machine tool, the combination with a reciprocating member, a main motor for operating the reciprocating member, and a feed motor for effecting feeding movements, of means for automatically operating the feed motor at each end of the stroke of the reciprocating member, and means for automatically delaying the operation of the feed motor at one end of the stroke of the reciprocating member.

3. In a control system for a machine tool, the combination with a reciprocating member, a cutting tool, a main motor for operating the reciprocating member, and a feed motor for effecting feeding movements of the cutting tool with respect to the reciprocating member, of means for automatically operating the feed motor at each end of the stroke of the reciprocating member, and means for automatically delaying the operation of the feed motor at the end of the cutting stroke of the reciprocating member.

4. In a control system for a machine tool, the combination with a reciprocating member, a main motor for operating the reciprocating member, a cutting tool, and a feed motor for effecting feeding movements of the tool, of means controlled by the reciprocating member for operating the main motor and for effecting movement of the feed motor at each end of the stroke of the reciprocating member, and means for automatically delaying the feeding movement of the feed motor at one end of the stroke of the reciprocating member.

5. In a control system for a machine tool, the combination with a reciprocating member, a main motor for operating the reciprocating member, and a feed motor, of means comprising a single portable switch having two switch members for operating each of the motors at will, means for operating the main motor in accordance with the movement of the reciprocating member and for automatically operating the feed motor at each end of the stroke of the reciprocating member, and means for automatically delaying the movement of the feed motor at one end of the stroke of the reciprocating member.

6. In a control system for a machine tool, the combination with a reciprocating member, a main motor for operating said reciprocating member, a cutting tool, and a feed motor for operating the cutting tool with respect to the reciprocating member, of means comprising a portable switch for controlling the operation of the main and the feed motor at will, means for operating the main motor in accordance with the operation of the reciprocating member and for automatically operating the feed motor at each end of the stroke of the reciprocating member, and means for automatically de-

laying the movement of the feed motor at one end of the stroke of the reciprocating member.

7. In a control system for a machine tool, the combination with a reciprocating member, a main motor for operating said reciprocating member, two main switches for operating the main motor in a forward and in a reverse direction and for completing a dynamic braking circuit therethrough, a feed motor, and two feed switches for controlling the operation of the feed motor, of means comprising a movable switch for controlling the operation of the main and feed switches at will, means for operating the main motor in accordance with the operation of the reciprocating motor and for automatically operating the feed motor at each end of the stroke of the reciprocating member, and means for delaying the movement of the feed motor at one end of the stroke of the reciprocating member.

8. In a control system for a planer, the combination with a reciprocating table, a main motor for operating said table, and a feed motor, of means for operating the main motor in accordance with the operation of the table, and automatic means for automatically effecting movement of the feed motor at each end of the table stroke, the operation of the feed motor being effected promptly at one end of the stroke and delayed somewhat at the other end of the table stroke.

9. In a control system for a planer, the combination with a reciprocating table, a main motor for operating said table, a cutting tool, and a feed motor, of means for operating the main motor in accordance with the table movements and for automatically effecting a feeding movement of the feed motor at each end of the table stroke, and automatic means for delaying the movement of the feed motor at the end of the cutting stroke of the table and for effecting a prompt movement of the feed motor at the end of the return stroke.

10. In a control system for a planer, the combination with a reciprocating table, a main motor for operating said table, and a feed motor, of means comprising a portable switch having two switch members for operating said motors at will, and automatic means for operating the main motor in accordance with the table movement and for operating the feed motor at each end of the table stroke, the operation of the feed motor being effected promptly at one end of the table stroke and delayed somewhat at the other end of the table stroke.

11. In a control system for a planer, the combination with a reciprocating table, a main motor for operating the table, a cutting tool, and a feed motor for effecting

feeding movement by the cutting tool, of means for automatically operating the main motor in accordance with the table movements and for effecting a feeding movement of the motor at each end of the table stroke, and means for delaying the movement of the feed motor at the end of the cutting stroke and for effecting a prompt movement of the feed motor at the end of the return stroke, and means comprising a portable switch having two switch members for controlling the operation of the two motors at will.

12. In a control system for a machine tool, the combination with a reciprocating member, a main motor for operating the reciprocating member, two main switches for operating the main motor in a forward and in a reverse direction, a feed motor, and two feed switches for operating the feed motor in a forward and in a reverse direction, of means for automatically operating said switches to reverse the main motor at each end of the stroke of the reciprocating member and to effect a feeding movement of the feed motor, and means for delaying the operation of one feed switch at one end of the stroke and for effecting a prompt operation of the other feed switch at the other end of the stroke.

13. In a control system for a machine tool, the combination with a reciprocating member, a main motor for operating the reciprocating member, two main switches for operating the main motor in a forward and in a reverse direction, a feed motor, and two feed switches for controlling the feed motor, of means for operating one of the main switches and one of the feed switches simultaneously at one end of the stroke of the reciprocating member and for operating a feed switch after the operation of a main switch at the opposite end of the stroke of the reciprocating member.

14. In a control system for a machine tool, the combination with a reciprocating member, a main motor for operating the reciprocating member, two main switches for operating the main motor in a forward and in a reverse direction, a feed motor, and two electro-magnetic switches for operating the feed motor in a forward and in a reverse direction, of means for operating the main switches to reverse the main motor at each end of the stroke of the reciprocating member, and means for energizing one of the feed switches through one of the main magnets to obtain a delayed feeding operation at one end of the stroke of the reciprocating member.

In testimony whereof, I hereto affix my signature.

HAROLD L. BLOOD.
